[57] CLAIM

The ornamental design for a garbage or waste bag holder, as shown and described.

DESCRIPTION

FIG. 1 is an exploded front perspective view of a garbage or waste bag holder showing my new design, the broken lines are for illustrative purposes only and form no part of the claimed design;

FIG. 2 is a front perspective view thereof;

FIG. 3 is a top plan view thereof with lid and mounting bracket removed;

FIG. 4 is a top plan view thereof;

FIG. 5 is a left side elevational view thereof, the right side elevational view being a mirror image of that shown; and

FIG. 6 is a front elevational view thereof.

FIG. I

FIG. 2

FIG. 3FIG. 4**FIG. 5**

FIG. 6
